DEVICE FOR CONVEYING MEDICAMENTS FOR THE DISINFECTION OF THE
URETHRA AND ITS VICINITY
Filed March 21, 1925

Robert Kanta,
Inventor
by his attorney
Mock, Black

UNITED STATES PATENT OFFICE.

ROBERT KANTA, OF VIENNA, AUSTRIA.

DEVICE FOR CONVEYING MEDICAMENTS FOR THE DISINFECTION OF THE URETHRA
AND ITS VICINITY.

Application filed March 21, 1925, Serial No. 17,183, and in Austria June 3, 1924.

The devices of a prophylactic kind ordinarily used, either only press or squirt the medicament into the urethra, whereupon same has to be closed in order to avoid the 5 medicament flowing back. Thus the very port of entrance of the infection, i. e., the transitory part where the exterior skin passes over into the mucous membrane, as well as the exterior environment of the 10 urethra are neglected, in fact, they are not brought into touch with the medicament at all on account of the clamping usually adopted for the closure. On the other hand, the prophylacticon is conducted to the 15 lower parts of the mucous membrane which cannot be infected on account of their distance from the entrance, thereby causing serious symptoms of catarrh through the irritation of the sensitive parts of the 20 mucous membrane. Therefore the employment of prophylactic mediums is rendered impossible on certain patients and, on the other hand, the usual devices fail, or offer only small reliability.

In order to avoid the above mentioned 25 defects the device for the conveyance of medicaments according to the present invention is of the shape like an impression of the glans top and of the end of the 30 urethra.

One mode of carrying out the present invention is shown in section on the accompanying sheet of drawing.

On a base *b*, adapted to the member and 35 made, for instance, of rubber, there is mounted a stopper *a*. The stopper, which which may be covered with rubber, together with its base represents the impression of a glans top and of the end of the urethra 40 and is coated with an adherent antiseptic medium of disinfection.

The device is best formed in such a way 45 that the portion to be inserted into the urethra is shaped as a blunt stopper, forming the extension of a grooving, excavation,

cavity or depression adapted to the shape of the top of the glans.

To use the device the stopper is inserted into the urethra. The disinfection effect of the medicament applied may be increased 50 considerably by turning the stopper slightly in the urethra that is through friction and, on the other hand, by allowing the stopper to remain some time in the entrance of the urethra. By turning the inserted device not only all infected parts and 55 pleats of the mucous membrane of the urethra are closely brought into touch with the medicament, but also the infected port of entrance, the transitory portion between 60 the exterior skin and the mucous membrane and the exterior environment of the urethra orifice. The medicament is prevented from penetrating too far to the sensitive parts 65 of the mucous membrane which are readily irritable and are therefore easiest disposed to develop catarrh, by reason of the base and the dimensions of the stopper. Since the tip of the device must be inserted into, and fit tightly within the body opening, 70 and since it is desirable to turn the stopper or applicator, it is important that the inner part thereof, to which the antiseptic is applied, should be soft and yielding.

The device may be used with or without 75 a handle as stopper to a recipient or receptacle for the prophylacticon. In order to complete the set, it can be recommended to include a piece of soap in the receptacle.

I claim—

An applicator for use in connection with the urethra comprising a recessed body having a contour conforming to the contour of the glans, said body having a projecting portion conforming to the contour 85 of the end of the urethra.

In testimony whereof I hereunto affix my signature.

DR. ROBERT KANTA.
